(57) **CLAIM**

I claim the ornamental design for a braking film dispenser with lobes, as shown and described.

DESCRIPTION

FIG. 1 is a top perspective view of the claimed design showing an exploded view of the claimed dispenser with a rotating member.

FIG. 2 is a bottom perspective view thereof showing an exploded view of the claimed dispenser with the rotating member.

FIG. 3 is a front elevation view thereof.

FIG. 4 is a rear elevation view thereof.

FIG. 5 is a right-side elevation view thereof, which is identical to a left-side elevation view thereof.

FIG. 6 is a top plan view thereof.

FIG. 7 is a bottom plan view thereof.

FIG. 8 is a sectional view thereof, taken along line 8-8 in FIG. 6.

FIG. 9 is a sectional view thereof, taken along line 9-9 in FIG. 6; and,

FIG. 10 is a perspective view of a system comprising two claimed dispensers, with one dispenser at each end of a stretch wrap dispensing roll.

The broken lines in the drawings depict unclaimed environmental subject matter.
